UNITED STATES PATENT OFFICE.

ULYSSES PRATT, FELIX A. DENISON, AND HORACE P. DENISON, OF DEEP RIVER, CONNECTICUT.

NAME-PLATE FOR ORGAN STOP-DRAWS.

SPECIFICATION forming part of Letters Patent No. 242,692, dated June 7, 1881.

Application filed October 4, 1879.

To all whom it may concern:

Be it known that we, ULYSSES PRATT, FELIX A. DENISON, and HORACE P. DENISON, of Deep River, in the county of Middlesex and State of Connecticut, have invented certain new and useful Improvements in Name-Plates or Labels for the Stop-Knobs of Organs and other Musical Instruments, of which the following is a full, clear, and exact description, reference being had to the accompanying drawings, forming part of this specification.

This invention relates to labels or name-plates for draw-knobs or "stops" of organs, melodeons, and other musical instruments. These name-plates, tablets, or labels, which serve to indicate the character of the stops, have heretofore been made of ivory or other suitable material, in the shape of flat plates or disks, on which the names of the stops are stamped or otherwise inscribed, and which are afterward cemented to or into the faces of the knobs proper, a piece of cloth being generally interposed between the plate and the wood to facilitate the adhesion of the cement. Name-plates thus made and secured are liable to become detached from the knobs to which they are applied.

Our invention consists in the combination, with the draw-knob or stop-knob of an organ or other musical instrument, of a name-plate provided on its back with a spur or stud, which is made to fit closely within a hole in the knob provided for its reception, and which enables the said plate to be more perfectly secured in place by the cement or adhesive material employed for the purpose. In order to save stock and obtain other advantages, when such name-plate is made of celluloid or other molded material, the invention further consists in making such spur hollow, to give it the character of a flange.

The invention also consists in the construction of such name-plate with a raised flange on its face, which not only serves to materially stiffen it, so that the body of the plate may be made thinner or lighter, but to also ornament the plate, and to conceal the cement or material used to secure said plate to the knob.

In the accompanying drawings, Figure 1 represents a perspective view of an organ-stop

constructed in accordance with our invention; Fig. 2, a longitudinal section of the same, and Fig. 3 an edge view of the name-plate detached. Fig. 4 is a sectional view of a modification.

A is the name-plate or label, which may either be made of ivory or other material that admits of being turned to bring it into shape, or which may be made of celluloid or other suitable composition that admits of being molded into the required form of the name-plate or label. It is preferred, however, to make it of celluloid or other composition of similar nature composed in part of a fibrous substance or substances, with the name of the stop molded in it, inasmuch as a name-plate or label of such material answers the purpose as well as one of ivory, which is a much more expensive substance, and is of course greatly superior to the cheap paper and glass labels that have been used on organ-stops in the place of ivory.

B is the knob proper, made of wood or any other suitable material, and to which the name-plate A may be secured by glue, shellac, or other adhesive material or cement.

Said name-plate A presents the usual form of a disk with the name of the stop marked on it; but it is formed at its back with a central spur or stud, b, which, when the plate is cemented in or applied to the face of the knob, tightly fits or is secured by cement within a hole, c, in the knob, and most effectually serves to prevent the accidental detachment of the name-plate from the knob. When said name-plate is made of ivory or other material that requires to be turned to bring it to the required shape, then the spur or stud b is solid; but when the name-plate is made of celluloid or other material that admits of it being molded into the required form, then said spur or stud may be made hollow, as shown in Figs. 2 and 4, in which case it may be made of a diameter nearly as large as that of the plate, in which case it assumes the character of a flange, as will be seen by reference to e e, Fig. 4.

Formed on and around the margin of the name-plate A is or may be also a raised flange, d, of a size that will cause it to closely fit within the recess in the knob, in which the body of the plate is inserted and secured. This

flange not only stiffens and ornaments the plate, so that the latter may be made thinner than usual, but it prevents any exposure at the edges of the plate of the glue or cement used to secure the plate to the knob, and gives a close finish.

We claim—

1. The combination, with the draw-knob or stop-knob of an organ or other musical instrument, of a name-plate or label having on its back a spur, stud, or flange which enters a cavity provided for it in the knob, substantially as and for the purpose herein described.

15 2. A name-plate or label for the stops of organs and other musical instruments, composed of a molded material or composition, and formed with a hollow spur, stud, or flange on its back, essentially as and for the purposes specified.

3. A name-plate or label for the stops of organs and other musical instruments, constructed with a raised flange on its face around the margin of the plate, substantially as and for the purposes described.
